UNITED STATES PATENT OFFICE.

SAMUEL RABIN, OF NEW YORK, AND JOHN M. LANG, OF YONKERS, NEW YORK.

BEATER AND MIXER.

1,373,761.

Specification of Letters Patent.

Patented Apr. 5, 1921.

Application filed February 3, 1920. Serial No. 355,946.

To all whom it may concern:

Be it known that we, SAMUEL RABIN and JOHN M. LANG, citizens of the United States, residing at New York city, Bronx county, 5 and Yonkers, Westchester county, respectively, and in the State of New York, have invented certain new and useful Improvements in Beaters and Mixers, of which the following is a specification.

10 This invention relates to beaters, and mixers and especially to portable devices for beating eggs, cream, and similar articles of food and its object is to rotate a beater whose spindle is journaled in the cap of a jar by 15 means of a screw that is pressed downward into a tube depending from said cap and containing a spring that returns the screw to its outer position.

The movement of the screw rotates a gear 20 wheel confined in the cap and which actuates a pinion at the top of the beater spindle to rotate the latter with both movements of the screw and in order to easily remove the beaten material the jar has an opening and 25 cap at one side.

These and other objects and details of the invention are more fully described in the following specification, set forth in the appended claims and illustrated in the accompanying drawings, wherein:

Figure 1 is a vertical sectional view of the improved device.

Fig. 2 is a plan view of the same.

Fig. 3 is a horizontal sectional view on the 35 line 3—3 of Fig. 1.

While beaters have been constructed whose motive power has been supplied by a screw, difficulty has been experienced in providing means to return the screw to its upper limit after such has been forced downward and the present invention is designed to not only return a vertically reciprocating screw but to protect it from the material being treated and to provide it with gearing to 40 be energized so that the beater may be permanently located and the whole carried by a removable cap.

The receptacle 5 is preferably a glass jar with a threaded neck 6, and having a lower 50 opening 7, on which is screwed a metal cap 8, containing the packing 9, to make it waterproof and prevent the escape of liquid contents. This opening is sufficiently elevated above the bottom of the jar to provide for 55 the average amount of cream or albumen to be contained therein without danger of leakage

and the opening is to allow the removal of the froth or beaten material without removing the upper cap 10, and the beating mechanism.

The cap 10, is screwed upon the neck 6, and is perforated at its center for the passage of the spindle 11, and its shank 12, the latter having at its upper end a pinion 13, and held in place by a plate 14, that is attached to the 60 upper side of the cap 10. The plate 14, also confines a gear wheel 15, perforated at its center so as to conform with the threads of a screw 16, that is adapted to play rapidly on account of its elongated threads in 65 the bearing 17, of plate 14, and a tube 18, that depends from the under side of the cap and which contains a spiral spring 19, that is adapted to be compressed by the screw, but which, when pressure 70 is removed, forces the screw upward and outward. The lower end of the tube 18, carries a loop 20, that forms the bearing for the lower end of spindle 11 and the latter carries the beater 21, that may be a frame of 75 sheet metal or wires and secured to the spindle.

The screw as it passes through the gear wheel 15, rotates the latter, which also turns the pinion 13 and rotates the beaters and 80 the rotation is reversed according to the way that the screw is moving. At the top of the screw is a knob 22, which is held against rotation by the hand of the operator and this 85 rigidity against rotation insures the proper 90 operation of the gear wheels and the beaters.

With this arrangement of gearing it is evident that a very high speed may be given the beater by proportioning the wheels and 95 it is obvious that the device may be otherwise arranged or modified without departing from the essential features above described or from the scope of the appended claims.

What we claim as new is:

1. In a beater and mixer, the combination of a container having a perforated cap, a depending tube below the perforation, a stem penetrating the cap and having beaters at one end and a pinion at the other end, a plate on the upper side of the cap and securing the pinion, a pinion held against the cap by the plate and having a threaded perforation, a screw working within the threaded perforation and the tube, and a return spring in the tube.

2. In a beater and mixer, the combination of a container cap, a stem journaled in the same and having beaters at its lower end, a pinion at the upper end of the stem, a perforated pinion gearing with the first pinion, a screw adapted to play through the second pinion and rotate it, a tube adapted to protect the screw from the contents of the container, and a spring in the tube adapted to return the screw to its normal position.

3. In a beater and mixer, the combination of a container cap, a stem journaled in the cap, beaters at the lower end of the stem, a tube adjacent the stem and bracing same at its lower end, a screw adapted to pass through the cap and play in the tube, a

spring to return the screw to the outside of the cap, a pinion on the screw and adapted to be rotated by it, a knob on the screw, a second pinion at the end of the stem and meshing with and adapted to be rotated by the first pinion, and a plate affixed to the cap and confining the pinions.

In testimony whereof, we have signed our names to this specification in the presence of two subscribing witnesses, this 24th day of January, 1920.

SAMUEL RABIN.
JOHN M. LANG.
